UNITED STATES PATENT OFFICE

169,148

COMBINATION DIRECTIONAL BLAST AND FLOOR CIRCULATOR FAN

Max E. Lautner, Webster Groves, Mo., assignor
to Knapp-Monarch Company, St. Louis, Mo.,
a corporation of Delaware

Application September 15, 1951, Serial No. 16,655

Term of patent 14 years

(Cl. D26—7)

To all whom it may concern:

Be it known that I, Max E. Lautner, a citizen of the United States, and a resident of Webster Groves, county of St. Louis, State of Missouri, have invented a new, original, and ornamental Design for a Combination Directional Blast and Floor Circulator Fan, of which the following is a specification, reference being had to the accompanying drawing, forming a part thereof, in which:

Figure 1 is a front elevational view of a combination directional blast and floor circulator fan showing my new design.

Figure 2 is a side elevational view thereof with the fan body adjusted for directional blast operation.

Figure 3 is a side elevational view thereof with the fan body and the combined base and deflector adjusted for floor-type circulation; and

Figure 4 is a top plan view of Figure 3 on a reduced scale.

The dominant features of my design reside in the portion shown by full lines on the drawing.

I claim:

The ornamental design for a combination directional blast and floor circulator fan, as shown and described.

MAX E. LAUTNER.
